United States Patent Office

Des. 203,994
Patented Mar. 8, 1966

203,994

TELEPHONE HANDSET

James D. Brandlein, Indianapolis, Ind., James N. Burlin, New York, N.Y., and Stanley E. Seretny, Indianapolis, Ind.; said Brandlein assignor to Western Electric Company Incorporated, New York, N.Y., a corporation of New York, and said Burlin and said Seretny assignors to Bell Telephone Laboratories, Incorporated, New York, N.Y., a corporation of New York

Filed Dec. 1, 1964, Ser. No. 82,866

Term of patent 14 years

(Cl. D26—14)

FIG. 1

FIG. 2

FIG. 3

FIG. 4

FIG. 1 is a front perspective view of a telephone handset, showing our new design;

FIG. 2 is a rear perspective view;

FIG. 3 is a front elevational view; and

FIG. 4 is a side elevational view, the opposite side being substantially a mirror image thereof.

The holes in the mouthpiece are continuous within the circular area indicated.

We claim:

The ornamental design for a telephone handset, substantially as shown and described.
